United States Patent Office.

WILLIAM E. WILCOX, OF PEORIA, ASSIGNOR TO HIMSELF AND T. H. WILLS, OF BEARDSTOWN, ILLINOIS.

Letters Patent No. 91,695, dated June 22, 1869.

IMPROVED ANTI-FRICTION ROLLER FOR SHAFTING.

The Schedule referred to in these Letters Patent and making part of the same.

To all whom it may concern:

Be it known that I, WILLIAM E. WILCOX, of Peoria, Peoria county, and State of Illinois, have invented new and useful Improvements in Anti-Friction Rollers for Boxes of Shafting; and I do hereby declare the following to be an exact description of the same, reference being had to the accompanying drawings, and to the letters of reference marked thereon, making a part of this specification, in which—

Figure 1 represents a vertical sectional front view of the box, with its sectional anti-friction rollers of cylindrical form.

Figure 2 is a sectional side view of the same.

Figure 3 represents a perspective view of one of the sections of the anti-friction rollers.

The nature of my invention consists in the construction of a shafting or carriage-axle box, with a divided series of anti-friction rollers in sections.

A is the box used in shafting, divided at the top, and the top attached by four screws, B, so as to be removed at any time when required. It is hollow, to contain the anti-friction rollers C and the circular apertures D, for the shafts or journals of shafts to revolve in.

E are circular plates at the ends of the rollers, in which the journals G of rollers C revolve in oblong

apertures H in the plates E. These circular plates E are divided into four sections, (four sections, more or less,) with their respective rollers.

The object of making the plates E, with their rollers C, in section, is for the purpose of inserting the sections into any close box around the shafting without removing the cranks or wheels of the shafting, which had to be done when the plates were solid, with their series of rollers all connected.

The apertures H in the plates E, in which the journals G of the rollers revolve, are made of an oblong shape, so that the rollers C can play freely, and be no strain on the plates E.

My invention is to use these sectional plates, with their rollers, in shafting or carriage-boxes.

What I claim as my invention, and desire to secure by Letters Patent, is—

The four sectional endless plates E, at each end, with their respective rollers C and journals G operating in the oblong slots H of each section, when arranged as herein described, and for the purposes set forth.

W. E. WILCOX.
